UNITED STATES PATENT OFFICE.

JOHN J. STESLICKI, OF DETROIT, MICHIGAN.

DESIGN FOR A CABINET.

42,717.

Specification for Design.

Patented July 2, 1912.

Application filed March 4, 1912. Serial No. 681,645. Term of patent 7 years.

To all whom it may concern:

Be it known that I, JOHN J. STESLICKI, a citizen of the United States, residing at Detroit, in the county of Wayne and State of Michigan, have invented a new, original, and ornamental Design for Cabinets, of which the following is a specification, reference being had to the accompanying drawing, forming part thereof.

The figure is a perspective of a cabinet showing my new design.

I claim—

The ornamental design for a cabinet, as shown.

JOHN J. STESLICKI.
